FIG. 1

FIG. 2

FIG. 3

To all whom it may concern:

Be it known, that I, Joseph D. Portanova, a citizen of the United States of America, residing at Arcadia, in the county of Los Angeles, State of California, have invented a new, original, and ornamental Design for a Portable Radio Cabinet or Similar Article, of which the following is a specification, reference being had to the accompanying drawings forming a part hereof.

Figure 1 is a top plan view of a portable radio cabinet or similar article showing my new design.

Figure 2 is a side elevational view thereof.

Figure 3 is a front perspective view thereof.

The rear of the cabinet is plain and unornamented.

The essential features of my design reside in those portions shown in full lines.

I claim:

The ornamental design for a portable radio cabinet or similar article, substantially as shown and described.
